CLAIM

The ornamental design for a sewing machine, as shown and described.

DESCRIPTION

FIG. 1 is a top, front-right perspective view showing the sewing machine of Applicant's new design.

FIG. 2 is a bottom plan view of the sewing machine of FIG. 1.

FIG. 3 is a left-side elevation view of the sewing machine of FIG. 1.

FIG. 4 is a top plan view of the sewing machine of FIG. 1.

FIG. 5 is a right-side elevation view of the sewing machine of FIG. 1.

FIG. 6 is a front elevation view of the sewing machine of FIG. 1; and,

FIG. 7 is a rear elevation view of the sewing machine of FIG. 1.

The broken lines in the drawings illustrate portions of the sewing machine which form no part of the claimed design.

1 Claim, 7 Drawing Sheets
